UNITED STATES PATENT OFFICE.

CHARLES KAHLMEN, OF ELIZABETH, NEW JERSEY.

MUSICAL APPARATUS.

Application filed October 11, 1924. Serial No. 742,968.

This invention relates to a musical device of the self-playing type, that is, it is operated by either an electrical motor or by foot pedals, and has a tracker bar or its equivalent for controlling by a perforated sheet or otherwise, the operation of a set of valves and their associated parts which, in turn, operate the piano action or the piano, the apparatus being designed also to receive a key operated reed instrument which may be of various kinds but I will limit this description and illustration to an accordion as the instrument to be played with or in lieu of the piano action.

The invention consists further in a holder and key operating mechanism for receiving the accordion so that the accordion when inserted in the apparatus, preferably when it has its bellows compressed, is in register with the key operating means so that it can be played. The invention also resides in dividing a connection from a self-playing apparatus to the accordion to provide the body thereof with suction in view of the operation of the bellows of the accordion so as to operate the reeds in the accordion so that they will give forth sound when their respective keys are operated.

The device is adapted to receive an accordion and particularly to receive it so that it can be readily attached or detached so that the accordion when lifted from the apparatus can be played manually, that is, as an accordion is usually played by hand.

The invention also consists in a selected means for operating either the piano or the accordion separately or both of them at the same time.

Another object of the invention is to provide a connection for the accordion which will provide for operating the swell or pedal of the accordion so as to control the volume of sound. A feature of this invention is in particular a musical device of the self-playing type with its key operating fingers disposed so as to operate the keys of an accordion and having a suction pipe acting in view of the bellows of the accordion to operate the reeds and a support for detachably securing the accordion in position so that it can be played.

The invention is illustrated in the accompanying drawing in which Figure 1 is a front view showing my improved invention mounted on a player piano. Figure 2 is a

diagrammatic view showing the parts of a player piano connected with the playing mechanism of the accordion and illustrating the accordion in position. Figure 3 is a section of the casing of the accordion playing device, the operating mechanism and the accordion being shown in elevation looking from the front and Figure 4 is a similar view but looking from the rear, this view, however, not showing the valve box, being taken on line 4-4 in Figure 6. Figure 5 is a section showing the valve box, being taken on line 5-5 in Figure 6. Figure 6 is a cross section taken on line 6-6 in Figure 4. Figure 7 is a detail view of one of the valves and is an enlarged view taken on line 7-7 in Figure 2.

The invention is adapted to be used with any of the forms of pneumatic player instruments and for the purpose of clear description I show it used on a player piano 10 the parts of which will only be described so far as they relate to its use with this invention and since the parts are well known in the art, they will not be described nor illustrated in detail except to the extent necessary to clearly describe the invention.

The player piano is provided with a pneumatic apparatus which can be operated in the usual way and I show foot pedals 11 for operating the main bellows or suction device 12, shown diagrammatically in Figure 2, which is connected by a pipe 13 with the wind chest (not shown and in rear of the tracker bar) and through it with the tracker bar 14 which tracker bar 14 is provided with note openings 15 which are connected by pipes 16 with their respective operating mechanisms 17 of the piano action so that they will sound the strings 18 by means of the hammers 19. The tracker bar is actuated by any of the usual types of player rolls 20 which have perforations that register with the openings 15 and thus sound the proper strings at the proper time to produce the melody.

My invention can be suitably disposed on such a pneumatic playing apparatus and I show a casing 21 which can be made ornamental and placed on top of a piano and has on its side portions the recesses 22 to receive the rolls 20, these recesses being closed by the doors 23. In the centre part of the cabinet I arrange the accordion 24, the accordion being of any of the usual

types and I show one having the bellows 25 for producing the wind pressure or suction to operate the reeds. The accordion 24 having a key board 26 which key board is usually arranged similar to the key board of a piano and at its other end a key board 27 having a series of spaced, round projecting keys, the keys on the key board 27 being adapted to be operated by the fingers of 10 the left hand and the keys on the key board 26 being adapted to be operated by the fingers of the right hand.

The accordion is usually readily attachable and detachable and for this purpose I 15 arrange the top 28 of the cabinet so that it can be removed, usually by hinging it as at 29 so that it can be swung open as shown in dotted outline in Figure 6. The accordion, when inserted in the instrument, is 20 held by suitable blocks 30 which can be arranged to engage it at the front and back at its bottom edge. When in position, the keys of the accordion are in register with their operating means, to be described here- 25 inafters.

A pipe 31 has one end detachable as at 32 and it is connected at its other end to the main suction bellows 12 and can have any suitable means such as the valve 33 for shutting off the air so that when desired, the accordion will not play as it will not have any suction to operate the reeds. This valve 33 is shut off when the accordion 24 is not to be played and is opened to cause the playing of the accordion in conjunction with 35 the piano.

When the piano is not to be played I swing the silence bar 34 down between the hammers 19 and the strings 18, the bar 34 being preferably hinged at 35 and is normally held in operative position by any suitable means such as the spring 36 but when it is to be put in silencing position, the handle 37 and the valve 38 are swung so as 40 to open the hole 39 in the valve casing 38 which connects with the pipe 40 and the bellows 41 is thus actuated as the pipe 42 connects it with the main bellows 12 and the arm 43 moves downward and swings the silencer bar 34 so that it is interposed between all the hammers and all the strings 45 of the piano.

For operating the keys of the accordion I arrange on one side the bellows 44, each 50 being operated from its respective valve 45, these valves preferably being arranged in a long valve box or casing 46 arranged along the back end of the casing 21 and being connected by pipes 47, each valve to its bellows, 55 and by a pipe 48 to its corresponding pipe 16 so that the notes of the piano and of the accordion will be in harmony when the instruments are played together. Each bellows 44 is provided with an arm 49 which 60 operates a rod 50 and the lever 51, each 65

lever having a finger or tab 52 which operates against its respective note, the lever 51 being pivoted at 53 on the bar 54.

On the other side of the accordion the bellows 55 operates similar to the bellows 44 and it will be understood that the bellows in each set are arranged in staggered relation so that they overlap so as to permit the levers being close enough together to register with the keys on the accordion which are 70 also close together. Each bellows 55 is connected by its pipe 56 with one of the valves 45 in the valve box 46 which also have their respective pipes 48 connecting with the pipes 16 of the piano action, as will be evident. 80

Each bellows 55 has an arm 49 and a rod 50 connected with the lever 51 which is pivoted similar to the lever 52 on the other side to the upright or bar 57. The valves 45 are of the usual type and I show one in 85 detail in Figure 7, the valve box 46 having the connection for the pipes 47 and 48 of the usual slip-on type, that is, it is simply a rubber tube slipped over small projecting metallic pipes 58. The valve 45 is of the usual 90 type and comprises a diaphragm 59, above which is the stem 60 extending into the upper chamber in which it supports the double-faced valve 61. The upper chamber is connected through the pipe 47 to a bellows 95 44 and the chamber below the diaphragm 59 is connected through the pipe 58, to the tracker bar. The opening 62 is closed when the valve 61 is raised. When the opening 100 in the tracker bar is uncovered the suction in the chamber of valve 45 lifts the diaphragm 59 which in turn raises valve 61. This closes the opening 62 and the suction 105 is then directed through pipe 47 to close the bellows 44 connected therewith.

To control the volume of sound of the music played on the accordion I provide means for operating the lever 63 which is mounted on accordions of this kind and for this purpose I provide a plate 64 which has a stud 65 operating in a slot on the end of the lever 63. The inner end of the lever with its connection for softening or making louder the notes of the accordion, is not shown as it is an old construction and usual 110 in accordions of the better kind. The plate 64 can slide as it is fastened through 115 slots 66.

A lever 67 slides the plate 64, being pivoted as at 68 and connected at its other end to a bellows 69. The bellows is operated through pipes 70 from the valves 71 in the valve box 72. The bellows 69 is a double one and the arm 67 is moved in two directions thereby, according to which bellows is operated by suction and these are selectively operated on account of the valves 71 being connected by the pipes 73 to opposite ends 120 of the tracker bar where the openings 74 are provided. 130

Of course, equivalents of this construction can be used but I prefer to show this as used in conjunction with the music roll that controls, by perforations therein, the loudness or softness of the music produced by uncovering the openings 74 in the tracker bar 14.

I claim:

1. A musical apparatus comprising a portable, keyed wind instrument with reeds operated by a bellows, in combination with a holder for said instrument, pneumatic suction means including valves, said means being arranged to register with the keys of the instrument to operate them when in the holder, a connection to operate the said reeds through the instrument and a tracker bar for selectively actuating the valves.
2. A musical device comprising a pneumatic player piano, an accordion, a holder for the accordion in which it is detachably secured, and a set of operating means actuated by the pneumatic means of the player piano and disposed so as to operate both on the reeds and the keys of the accordion.
3. The combination of a player piano, with an accordion, the accordion being detachable from the piano, the piano having pneumatic means for its playing and a connection for the operation of both the reeds and the keys of the accordion by said pneumatic means.
4. The combination of a player piano having a pneumatic operating mechanism, said mechanism including an additional key

operating means, and having a support for holding a portable manually operable reed instrument, with such instrument which when in position is operated as to its keys by the additional key operating means, and a pipe for operating the reeds of the instrument.

5. The combination of a player piano having a pneumatic operating mechanism, said mechanism including an additional key operating means, and having a support for holding a portable manually operable reed instrument, with such instrument which when in position is operated as to its keys by the additional key operating means, and a pipe for operating the reeds of the instrument, a tracker bar common to both sets of playing mechanism, and means for selectively operating these sets.

6. A musical device, an accordion, a holder for the accordion, a set of bellows and valves for registering with the keys of the accordion when it is in the holder, a pipe connected to the accordion for the operation of the reeds by air, and a tracker bar and main suction means connected to the set of valves and bellows of the accordion operating means, the pipe being connected to said main suction means.

In testimony that I claim the foregoing, I have hereto set my hand, this 25th day of September, 1924.

CHARLES KAHLMEN.
